ALWIN MITTASCH, OF MANNHEIM, WALTER FRANKENBURGER AND FRITZ WINKLER, OF LUDWIGSHAFEN-ON-THE-RHINE, GERMANY, ASSIGNEES TO I. G. FARBNINDUSTRIE AKTIENGESELLSCHAFT, OF FRANKFORT-ON-THE-MAIN, GERMANY, A CORPORATION OF GERMANY

PRODUCTION OF LIQUID HYDROCARBONS OF LOW BOILING POINT FROM OLEFINES

Application filed February 17, 1927, Serial No. 169,128, and in Germany February 20, 1926.

This invention relates to the production of liquid hydrocarbons of low boiling point (including those of the aromatic series) from olefines, or gases containing the same, with 5 the assistance of catalysts and with or without the aid of pressure.

It is known that gaseous olefines can be converted into liquid hydrocarbons by exposing them to elevated temperatures and, if desired, 10 to elevated pressures. This method of working, however, is in no way satisfactory, as the speed of the reaction and the yield of liquid products are comparatively small; further, a 15 considerable portion of the olefines is converted into methane and carbon and is thereby lost for the desired purpose.

We have now discovered a number of catalysts, with the aid of which the said difficulties can be overcome to a large extent. The 20 first group of catalysts suitable for the said reaction consists of the noble metals and copper. It is advisable that these metals should not be employed in a state of more or less fine division, but preferably in such a 25 form as to exhibit more or less large coherent surfaces. For example, copper turnings, copper wire gauze, silver turnings, gold and the like may be advantageously so used; a 30 copper tube, for example, also exerts the desired catalytic action. Other valuable catalysts are compounds and particularly oxygen 35 compounds of the alkali metals. Compounds of potassium, rubidium and cesium are particularly active for this purpose, but compounds of sodium and of lithium may also be used with advantage. Mixed catalysts containing salts or oxids of other metals in addition to the said alkali compounds are 40 preferably employed. The salts of the oxygen acids of phosphorus, and also those of boron and antimony, are particularly effective not only when they contain the alkali metals but also when they contain other 45 metals as the basic constituent. Even the acids themselves, or their anhydrids on carriers, act in a similar manner, as do also the reduction products of the salts, which may be formed spontaneously in many cases in practice by the action of reducing gases. For 50 example, calcium phosphate, zinc antimonate

or copper borate, and the like, or also mixtures of these or similar compounds, may be used.

The production of liquid hydrocarbons of 55 low boiling point from the olefines may be effected under any suitable pressure. The temperature to be employed depends on the composition of the gases, on the nature of the catalyst and on the pressure. As a rule, the 60 operation may be carried out at a temperature up to 900° C. when the amount of olefines in the gases is small, and up to 800° C. when the content is higher and when employing elevated pressure. The most suitable temperatures generally range between 200° and 700° 65 C. The conversion according to the present invention is carried out in the absence of substantial amounts of free oxygen.

According to the temperature prevailing 70 during the conversion, liquid products of varied nature will generally be obtained. When working at low temperatures, such as from 300° to 400° C., the products usually 75 contain large amounts of liquid olefines and the amount of naphthenes and benzol hydrocarbons is usually very small. It increases considerably, however, with a rise of temperature, and, at about 550° C. only small 80 quantities of unsaturated compounds are still present, the bulk of the products consisting of benzol hydrocarbons and naphthenes in varying proportions. The transformation of olefines or gases containing the same into liquid hydrocarbons of low boiling point proceeds with particular advantage if materials 85 giving rise to the separation of carbon be excluded from the reaction. For this purpose the interior of the hot portions of the iron or steel apparatus employed may be lined for example with copper, silver, quartz, ferro-silicon or other like materials.

Since more or less small quantities of methane may be formed as an undesirable product from the olefines during the process, it has been found advantageous to counteract 95 this undesirable reaction by adding methane itself, or gases which furnish methane, such as the oxids of carbon together with hydrogen if necessary. The undecomposed residual gas may be passed, after the separation of 100

the condensable hydrocarbons, through another pressure apparatus, or returned to the cycle of operations in the same apparatus.

Under certain circumstances it is preferable to eliminate from the crude gases containing the olefines, such fractions as are especially rich in polymerisable constituents, such as ethylene, propylene, acetylene, ethane, propane, and the like, by special treatment 10 in any suitable manner, in particular by fractional liquefaction or by adsorption by means of active charcoal or silica, and then to subject these gas mixtures separately to the conversion into liquid hydrocarbons.

15 The hydrocarbons remaining in the gases after separation of the liquid products formed may also be recovered and treated for themselves as aforescribed, instead of passing the residual gas directly through another 20 or, in a circular course, through the same re-action apparatus.

When industrial gases containing sulfur are used, the elimination of the sulfur is particularly beneficial.

25 The following examples will further illustrate how the said invention may be carried into practical effect, reference being had to the accompanying diagrammatic drawing showing by way of example one type of apparatus suitable for carrying out the invention, but the invention is not limited to these examples.

Example 1

35 Brown-coal-tar oil supplied from the container A is heated to about 700° C. in a retort B. The disengaged gases are cooled in a cooler C and the liquid constituents namely water and oils separated in the vessel D. The 40 gases are passed to a compressor E where they are compressed to about 50 atmospheres, and are then led through a pressure tube which is lined with a copper tube F and heated from outside to 500° C. Abundant quantities of 45 liquid hydrocarbons, consisting chiefly of benzol hydrocarbons, benzines and naphthenes, are separated by a cooler G and collected in a vessel H under pressure whilst the residual gas is returned to the pressure tube 50 by a circulation pump I. In order to prevent the gas in circulation from becoming too heavily charged with nonreactive constituents, a certain portion of it is drawn off from time to time by a pipe K, and suitably treated, for example with active charcoal in a container L in order to recover the valuable constituents still therein, such as olefines and the like for the purpose of returning them to the process. The nature and yield of the 60 valuable liquid hydrocarbons produced depend primarily on the temperature employed.

Example 2

Brown-coal-tar is injected into a current 65 of steam superheated to 400° C. The tar,

to a large extent vaporized, carried away by the steam is then passed through a 2-inch tube of ferrosilicon, heated to 950° C. in which the transformation into gaseous hydrocarbons takes place. The issuing mixture of gases 70 and steam is cooled in order to condense the steam, its composition then being 4 per cent of carbon dioxid, 15 per cent of ethylene, 7 per cent of propylene and butylene, 7 per cent of carbon monoxid, 36.6 per cent of hydrogen, 75 9.6 per cent of methane and 20.8 per cent of nitrogen. This gas is next conducted at ordinary pressure, and at a temperature of about 850° C. over a catalyst composed of pumice and potassium bichromate, which treatment 80 results in the production of a liquid which boils below 80° C. and contains up to 90 per cent of benzene.

The brown-coal-tar may be replaced by other materials such as coal tar, low-tempera- 85 ture tar, and the like.

Example 3

A gas consisting of 3 per cent of carbon dioxid, 35 per cent of ethylene, propylene 90 and butylene, 7 per cent of carbon monoxid, 23 per cent of hydrogen, 20 per cent of methane, and 12 per cent of nitrogen, is passed, at a temperature of 850° C. and at the rate of 10 to 13 litres an hour, through a copper tube with an internal diameter of 20 millimetres, and containing if required a roll of copper wire gauze 20 centimetres in length. One-third of the heavy hydrocarbons are transformed, in a single passage, into a liquid 95 100 containing only 5 per cent of tar. After the tar has been removed, this liquid boils below 150° C., and consists of approximately 60 per cent of benzene and 40 per cent of benzine. No carbon is deposited on the walls of the 105 tube or on the copper gauze.

An extensive transformation without deposition of carbon can also be obtained by the use of silver and gold.

Example 4

110 Gases containing ethylene, propylene, and the like, such as are readily obtained, for example, by the partial liquefaction and rectification of coke-oven gases, are passed under ordinary pressure and at a temperature of 680° to 700° C. over granulated potassium phosphate (for example dipotassium phosphate). A liquid condensate containing a large proportion of hydrocarbons of low boiling point, especially benzol hydrocarbons, associated with smaller quantities of aliphatic hydrocarbons, can be recovered from the reaction gas. The product may be further treated, for example, purified or hydro- 120 125 genated, before use, if necessary. Natural gases, low-temperature distillation gases, cracking-process gases, oil gases, coke-oven gases, and the like, and also gases containing ethylene, and the like, and produced by any 130

other convenient way, for example from methane, may be used as the gaseous mixtures containing olefines.

Example 5

5 An oil gas containing about 46 per cent of methane, 36 per cent of unsaturated hydrocarbons, 10 per cent of hydrogen and 4 per cent of carbon monoxid, together with small quantities of carbon dioxid, oxygen and nitrogen, is passed, under ordinary pressure, at the rate of 25 litres an hour, through a quartz tube, 1 metre in length and 3 centimetres internal diameter, the middle section of which, for a length of 60 centimetres, is filled with 15 a mixture of calcium pyrophosphate and copper bronze, this portion of the tube being surrounded by an electric furnace 80 centimetres in length. The gas issuing from the contact chamber, which is heated to from 630 to 670° C. is passed through two condensing vessels cooled with a mixture of ice and common salt, and through 8 to 10 such vessels cooled with a mixture of acetone and carbon dioxid. About 85 per cent of the unsaturated hydrocarbons contained in the original gas are transformed into a liquid product containing up to 70 per cent of benzene, together with naphthalene and tar.

20 30 A similar effect is obtained with borates, such as copper borate, as also with free acids or anhydrids, such as boric acid or phosphorus pentoxid, deposited on pumice. When these substances are used, the formation of soot which occurs when many other substances are employed, especially the majority of metals, is no longer apparent, but only deposits of foliaceous carbon with a metallic lustre are formed.

25 40 What we claim is:

1. The process of producing liquid hydrocarbons of low boiling point, which comprises heating gases comprising olefines at between about 200° and 900° C. and while excluding substantial amounts of free oxygen with a catalyst comprising at least one of the constituents from the group consisting of noble metals and copper, said metals being employed in a form exhibiting coherent surfaces.

45 50 55 2. The process of producing liquid hydrocarbons of low boiling point, which comprises heating gases comprising olefines at between about 200° and 800° C. and while excluding substantial amounts of free oxygen with a catalyst comprising at least one of the constituents from the group consisting of noble metals and copper, said metals being employed in a form exhibiting coherent surfaces.

60 65 65 3. The process of producing liquid hydrocarbons of low boiling point, which comprises heating gases comprising olefines at between about 200° and 900° C., under a pressure in excess of atmospheric pressure with a catalyst comprising at least one of the constituents from the group consisting of noble metals and

copper, said metals being employed in a form exhibiting coherent surfaces.

4. The process of producing liquid hydrocarbons of low boiling point, which comprises heating gases comprising olefines in the presence of methane at between about 200° and 900° C. and while excluding substantial amounts of free oxygen with a catalyst comprising at least one of the constituents from the group consisting of noble metals and copper, the said metals being employed in a form exhibiting coherent surfaces.

70 75 80 5. The process of producing liquid hydrocarbons of low boiling point, which comprises heating gases comprising olefines in the presence of compounds furnishing methane at between about 200° and 900° C. and while excluding substantial amounts of free oxygen with a catalyst comprising at least one of the constituents from the group consisting of noble metals and copper, the said metals being employed in a form exhibiting coherent surfaces.

85 90 95 6. The process of producing liquid hydrocarbons of low boiling point, which comprises heating gases comprising olefines, while preventing the materials undergoing treatment from coming into contact with free iron while at high temperatures, at between about 200° and 900° C. and while excluding substantial amounts of free oxygen with a catalyst comprising at least one of the constituents from the group consisting of noble metals and copper.

100 105 7. A process for the production of liquid hydrocarbons of low boiling point, which comprises passing gases containing olefines into contact with a coherent surface of copper, at a temperature of about 500° C. under a pressure of 50 atmospheres and while excluding substantial amounts of free oxygen.

In testimony whereof we have hereunto set our hands.
